UNITED STATES PATENT OFFICE.

WILLIAM G. HAFNER, OF CLAY, NEW YORK.

BARK-ROSSING MACHINE.

1,102,657.

Specification of Letters Patent.

Patented July 7, 1914.

Application filed December 18, 1912. Serial No. 737,383.

To all whom it may concern:

Be it known that I, WILLIAM G. HAFNER, of Clay, in the county of Onondaga and State of New York, have invented a new and useful Bark-Rossing Machine, of which the following is a specification.

This invention has for its object the production of a bark rossing machine which is particularly simple in construction, and highly efficient and rapid in operation; and the invention consists in the combinations and constructions hereinafter set forth and claimed.

In describing this invention reference is had to the accompanying drawings in which like characters designate corresponding parts in all the views.

Figure 1 is a front elevation, partly broken away, of one embodiment of my invention. Fig. 2 is a side elevation, partly in section, looking to the right in Fig. 1. Fig. 3 is a fragmentary view of parts seen in Fig. 1, parts being omitted, illustrating particularly the means for gripping and carrying away the removed bark. Fig. 4 is a front elevation of the rotatable member carrying the bark removing means. Fig. 5 is a sectional view on line "A—A," Fig. 4. Fig. 6 is an elevation of a modified form of the bark removing means seen in Fig. 4.

This bark rossing machine comprises, generally, a rotating member having a passage through which the branches are passed, means carried by said member and projecting into the passage to remove the bark, means for carrying away the removed bark from one end of the passage of said member, means for feeding the branches through the passage, and means for actuating the feeding means, the rotating member and the means for carrying away the removed bark. However, some of the foregoing parts may be omitted if desired.

1 is the frame of this machine, which may be of any desirable form, size and construction.

2 designates the rotating member having an axial passage 3 through which the branches are passed, the member 2 having a hub 4 detachably secured as by screw threads to the body of said member 2, and this hub being journaled in a suitable bearing 5 formed in a supporting bracket 6 supported by the frame 1 near the front side thereof. The hub 4 is shown as provided with a peripheral surface for receiving the power to

rotate the member 2, this surface being shown as sprocket teeth 7. In this embodiment of my invention, I have shown a double machine, that is, one having two rotating members 2, and double feeding and bark carrying away means, all driven from a common power shaft, and a description of one set of mechanism will be sufficient for both.

The means carried by the member 2 and projecting into the passage 3 for removing the bark from the branches comprises preferably a pair of jaws 8 projecting into the passage 3 near the receiving end thereof, these jaws being here shown as sliding in radially extending guides 9 formed in the front face of the member 2 and as being pressed toward each other by springs 10. The guides 9 are covered by suitable plates 11 which are held in position by screws 12. The jaws are formed with faces 13 inclining from their outer sides toward the center of the passage and terminating in edges 14 which normally meet in a straight line crossing the passage and engage the branches, these faces 13 facing outwardly in order to engage the advance ends of the branches being passed into the passage 3. The faces 13 act together as a funnel to guide the branches between the jaws as the branches are being pushed into the passage 3, said faces 13 forming comparatively sharp edges on the opposing faces of the jaws 8; and owing to the rotation of the member 2 carrying the jaws 8, the edges loosen the bark, and owing to the feeding movement of the branches through the passage 3 the loosened bark is scraped off.

The springs 10 are located in lengthwise slots 15 in the bodies of the jaws and each spring is interposed between one end of the corresponding slot 15 and a pin 16 projecting from the bottom of the corresponding guide or channel 9 into the slot near the other end thereof, the springs being strong enough to overcome the centrifugal force of the member 2 and to press the jaws toward each other and hold the same engaged with the branches. However, as seen in Fig. 6, the jaws may be arranged with their heads located on the opposite sides of the center of the member 2 from the sides on which their body portions are located, in order that the centrifugal force may be utilized to draw the heads of the jaws toward each other.

The means for carrying away the removed bark from the entrance end of the passage

comprises two members arranged on opposite sides of the passage, that is, above and below the same, one as the upper member being movable toward the other across the 5 passage to grip the removed bark, at the entrance end of the passage, between the same and the other member, and the two members being then movable downwardly together until the bark has been carried away from 10 the member 2, and said two members then separating permitting the bark to drop beneath the machine, whereupon the gripping members are returned to their normal position.

15 The gripping members consists of jaws 17 and 18 carried respectively by reciprocating parts 19, 20 extending upwardly, the support for the upper jaw 17 being connected to a lever 21, Fig. 1, pivoted between 20 its ends at 22 to a suitable bearing supported by the frame 1, this lever 21 having an arm 23 arranged to be engaged by the power driven means to be described, and another arm 24 to which is connected a returning 25 weight 25. The other support 20, is connected at its upper end to a returning spring 26 suspended from a yoke 27 at the top of the frame of the machine.

In operation, the jaw 17 is moved downwardly by the lever 21 across the passage 30 and grips the accumulated bark between its lower edge and the upper edge of the jaw 18 whereupon the downward movement of the jaw 17 is transferred to the jaw 18 until 35 the jaw 18 engages a stop 29 provided on the frame, Fig. 3, when the weight 25 is permitted to raise the upper jaw and hence separating the jaws and permitting the bark to drop. The weight 25 and spring 26 then 40 return the jaws to their starting position. The weight 25 is arranged to act quicker than the spring 26 so that the upper jaw will open faster than the lower jaw will close. The jaws 17 and 18 are controlled 45 and timed in their operation by the projection 67 on the wheel 66 and the operator inserts the branch between the jaws 8 immediately after the jaws 17 and 18 have opened and as there is but one projection 67 50 and the wheel 66 is large and revolves comparatively slowly, there is ample time for the branch to pass through the member 2 before the jaws 17 and 18 again close. The jaws 17 and 18 for both rotating members 55 2 in the double construction here shown are supported by one set of supports 19 and 20. The means for feeding the branches into the passage 3 includes two sets of rollers 30, 31 arranged in front of the passage 3, the 60 rollers being arranged at an angle, usually at a right angle to each other, and the planes coincident with the points of tangency of the pairs intersecting in a line substantially coincident with the axial line of the passage 3. 65 A guide as a tube 32 is also arranged in ad-

vance of these rollers with its axis alined with the axial line of the passage 3. The means for feeding the rollers also includes means for drawing the branches through the passages, this means including two sets of 70 rollers 33 and 34 spaced apart, and a tube 35 interposed between the pair of rollers and arranged with its axis substantially coincident with the planes of tangency of the rollers 33 and 34 and with the axis of the 75 passage 3.

The actuating means includes a power shaft 36 journaled in suitable bearings in the frame, and power transmitting means between this shaft and the various moving 80 parts of the machine.

The power-transmitting means between the shaft 36 and the rotating members 2 includes a sprocket wheel 37 mounted on said shaft and connected by a sprocket chain 38 to a sprocket wheel 39 mounted on a shaft 40 journaled in a suitable bearing located directly above one of the members 2, additional sprocket wheels 41 on the shaft 40 and connected by sprocket chain 42, Fig. 3, 90 to the sprocket teeth 7 on the hub 4 of the member 2.

The motion from the shaft 40 is transmitted to a similar shaft 43 which drives the other member 2, by means of intermeshing gear wheels 44 and 45 mounted on the shafts 40 and 43 respectively, and the shaft 43 is connected to its corresponding member 2 by a sprocket wheel and chain 41 and 42.

100 The vertical feeding rollers 30 are driven from the power shaft 36, by means of a sprocket wheel 46 on said shaft 36 and connected to a shaft 47, journaled in a bearing in the lower part of the frame, by means of a sprocket chain 48 running over the wheel 46 and a sprocket wheel 49 on the shaft 47, and the shaft 47 is connected to the first set of vertical rollers by means of a beveled gear 50 thereon meshing with the beveled gear 51 at the lower end of a vertical shaft 52 journaled in suitable bearings in the frame, and having a power-transmitting wheel as a pulley at its upper end which is connected by a belt 54 to a pulley 55 mounted on the upper end of the axle 56 of one of the rollers 30 of the first set of vertical rollers, the motion of the axle 56 being transferred to the axle 57 of the other roller by intermeshing gears 58 and 59. The axle 110 56 is connected to the axle 56 of one of the other vertical rollers by means of pulleys 60 and 61 mounted respectively on said axles and a belt 62 connecting the pulleys; and the rollers 30 of the second set are connected by 115 gears similar to the gears 58 and 59.

120 The horizontal rollers 31 are rotated by means of a beveled gear 63 mounted on the axle of one of said rollers 31 and meshing with the beveled gear 50, and the axles of 125 130

the rollers 31 are connected by intermeshing gears 64 and 65.

The shaft 47 extends from front to rear of the machine and is provided with two additional beveled gears 50 located in position to mesh with the beveled gears 63 mounted on the ends of the lower rollers of each pair 33 and 34.

The means for actuating the lever 21 to 10 depress the jaws 17 and 18 comprises a wheel 66 having a cam or projection 67 on one side thereof arranged to pass under the arm 23 of the lever 21 and hence raise the rear end of the lever against the action of 15 the weight 25 and depress the front end of said lever to effect the operation of the jaws 17 and 18 as described. The wheel 66 is operated with sprocket teeth and is connected to a sprocket wheel on the shaft 47 by a 20 chain 68.

In operation, the operator passes the branches into the passages 3 at the same time and during the rotation of the members 2, the bark is wholly removed by the jaws 8 25 and accumulates in front of the members 2, and the branches having passed through the passages 3, the jaws 17 and 18 descend and carry away the removed bark, the operator gaging the time in which he places the 30 branches in the passages so that the branches will have entirely passed through the passage by the time the jaws operate.

What I claim is:

1. A bark rossing machine comprising a 35 rotating member having an axial passage through which the branches are passed, and jaws carried by the member and projecting into the passage and movable substantially radially in opposite directions relatively 40 thereto, the jaws having inclined faces facing the entrance of the passage, these faces providing on the jaws opposing comparatively sharp edges for engaging the branches, the edges normally meeting in a straight 45 line and the faces serving as a funnel to engage the ends of the branches and guide the same between the jaws, substantially as and for the purpose described.

2. A bark rossing machine comprising a

member formed with a passage through 50 which the branches are passed, means for removing the bark from the branches while passing through the passage, jaws movable crosswise of the member for gripping the removed bark at the entrance 55 end of the passage after the branches have passed through the passage and moving the bark to one side of the passage and releasing the same, and means for operating the jaws, substantially as and for the purpose specified. 60

3. A bark rossing machine comprising a rotating member formed with a passage through which the branches are passed, means associated with said member for removing the bark from the branches passing through said passage, and means movable across the face of said member and across the entrance end of said passage for engaging the removed bark accumulating at the 70 entrance end of the passage and carrying the same to one side of the passage, substantially as and for the purpose set forth. 75

4. A bark rossing machine comprising a member having a passage through which the 75 branches are passed, means for removing the bark from the branches while passing through the passage, means for carrying away the removed bark from one end of the passage, the last-mentioned means comprising a pair of jaws located on opposite sides of the passage, and means for moving one jaw across the passage toward the other jaw, and moving both jaws simultaneously to carry the bark gripped thereby to one side 85 of the passage, and for opening the jaws, and then returning the same to their normal position, substantially as and for the purpose specified. 80

In testimony whereof, I have hereunto 90 signed my name in the presence of two attesting witnesses, at Syracuse, in the county of Onondaga, and State of New York, this 14th day of December, 1912.

WILLIAM G. HAFNER.
